UNITED STATES PATENT OFFICE.

FRANK W. STEVENS, OF NEWTON, MASSACHUSETTS, ASSIGNOR, BY DIRECT AND MESNE ASSIGNMENTS, TO HERBERT C. VENO, OF NEWTON, MASSACHUSETTS.

FORM FOR CONCRETE STRUCTURES.

Application filed October 4, 1923. Serial No. 666,597.

This invention relates to forms for concrete and similar structures, and especially, although not exclusively, to forms for use in foundation work, and has for its object 5 to provide a light, inexpensive, economical and generally-satisfactory sectional metallic form for use in substitution for the wooden cribbing usually employed for this purpose and which is very expensive as to both material and labor. More particularly, the invention has for its objects to provide a sectional metallic form consisting of a suitable number of sections or units of a variety of forms, all of which may be inexpensively 10 produced from plates and standard structural shapes, which sections or units may be easily and quickly assembled to constitute a form for a wall in accordance with substantially any plan, which form, when set up, is 15 securely supported and braced and is otherwise of sufficient strength to perform its intended function, and which can be as readily disassembled after the wall has set, the sections being capable of repeated use in different 20 assembled relationships for an indefinite period, and being practically indestructible.

The foregoing and other objects of the invention, together with means whereby the same may be carried into effect, will best be 25 understood from the following description of one embodiment thereof illustrated in the accompanying drawings. It will be understood however that the particular construction and arrangements described and shown 30 have been chosen for illustrative purposes merely, and that the invention, as defined by the claims hereunto appended, may be otherwise practised without departure from the spirit and scope thereof.

40 In said drawings—

Figs. 1, 2 and 3 are, respectively, a side elevation, an edge elevation, and a plan view of one of the flat panel sections.

Figs. 4 and 5 are sections taken on the 45 lines 4—4 and 5—5, respectively, Figs. 1 and 2.

Figs. 6 and 6^a are fragmentary side views similar to Fig. 1 of similar panel sections of different widths.

50 Fig. 7 is a plan view of the panel section shown in Fig. 6^a.

Figs. 8 and 9 are perspective views of two of the horizontal angle bars employed for supporting, alining and bracing the assem-

bled form, said figures showing bars of different lengths.

Fig. 10 is a side elevation, partly in section and partly broken away, of several assembled panel sections.

Fig. 11 is a section on the line 11—11, 60 Fig. 10.

Fig. 12 is a perspective view of one of the outside corner sections.

Fig. 13 is a perspective view, partly broken away, of one of the inside corner units. 65

Fig. 14 is a perspective view of an assembly of the units shown in the preceding figures to constitute a form for a short angular section of wall.

Fig. 15 is a detail horizontal sectional view 70 illustrating means for tying together opposite sides of the form.

The form herein shown comprises a suitable number of sections of different shapes which may be assembled to build up a form 75 of any desired size and configuration, together with keys for connecting the assembled sections, and members for alining the sections and supporting and bracing the form as a whole.

As herein shown, the sections comprise flat, side and end panels which form the straight sides and ends of the wall, outside corner members for connecting the panels at the exterior corners or angles of the wall, 85 and inside corner units for forming the interior angles.

In Figs. 1 to 5 is illustrated a flat panel section indicated as a whole by the numeral 20. Said panel comprises a rectangular 90 metal plate 21 of a length corresponding to the desired height of the form and whose width may, as hereinafter explained, vary in accordance with the desired width of the panel of which it forms a part. Secured, as 95 by spot-welding, to the upper and lower edges of the plate 21, are channel bars 22, while similarly secured to the lateral or vertical edges of said plate are angle bars 23, said channel and angle bars constituting a 100 strengthening or stiffening frame for the panel. The angle bars 23 are disposed with their flanges which are secured to the plate 21 turned inwardly or toward one another, while the other flanges are turned outwardly 105 parallel to one another and constitute outwardly projecting flanges at the extreme edges of the panel. Said outwardly project-

ing flanges are formed intermediate their ends with a suitable number of preferably closed slots 24 and at both of their extreme ends with open slots 25.

5 Panel sections such as that above described are made of various widths, the panel 20 being relatively narrow, and the panels 200 and 201, illustrated in Figs. 6, 6^a, and 7, being of greater widths. The 10 particular panels shown are merely illustrative of various widths in which the sections can be made, all of such sections being of the same length or height irrespective of their width. Said panel sections are assembled to constitute straight 15 portions of the form, the panels 200, 201, etc. being side panels, and the panels 20 constituting end panels and being also used as side panels where short lengths are required, as shown, for example, in Fig. 10, where one panel 20 is assembled with two panels 200.

Cooperating with the panel sections, for 20 the purpose of alining and bracing the same and to constitute a top and a base for the assembled form, are angle bars which are provided in a plurality of lengths, two being shown at 27 and 270 in Figs. 8 and 9, and others being shown at 271 and 272 in Fig. 30. When a plurality of panels 20, 200, etc. have been assembled in alined relationship, as shown in Fig. 10, an angle bar 27, 270, etc. is placed horizontally and longitudinally of the series at both the top and bottom thereof, one flange of said bar being inserted in the alined end slots 25 of the abutted flanges 23 of the contiguous sections, the other flange of said angle bar overlying and engaging the ends of said flanges 23, as shown in Fig. 11.

The outside corner sections comprise angle bars 28 (Figs. 12 and 14) of a length corresponding to the height of the panel sections, the flanges of said angle bars being formed intermediate their ends with slots 240, corresponding in number and arrangement to the slots 24 in the flanges 23, and in their ends with open slots 250 corresponding to the slots 25 of said flanges 23.

50 Each inside corner section, designated as a whole in Figs. 13 and 14 by the numeral 29, comprises a permanently assembled unit consisting of two plates 30 disposed at an angle to one another and the inner or proximate edges of which are secured to a vertical angle bar 31. To the outer edges of said plates are secured vertical angle bars 32 which are similar in form and arrangement to the angle bars 23 of the panel sections, said bars being formed intermediate their ends with slots 241 corresponding to the slots 24 and in their ends with open slots 251 corresponding to the slots 25. The interior angle of the unit thus constructed 55 is braced at the top and bottom of said

unit by an angular channel bar 220, corresponding to the channel bars 22 of the panels.

The several sections above described are secured together in assembled relationship 70 by bifurcated gravity keys 35, whose form is most clearly shown in Fig. 10. Each of said keys comprises a flat metal stamping of U-shape including a head 350 having rounded corners and depending legs 351 the 75 opposite inner edges 352 of which converge toward the head 350. When the contiguous flanges 23, 28, 32, etc. of adjoining sections are placed in abutted engagement, with the slots 24, 240, 241, etc. in register with 80 one another the keys 35 are inserted laterally through the registering slots, as shown at the upper left-hand corner of Fig. 10, the rounded heads 350 facilitating such insertion, and the depending legs 351 caused 85 to embrace the abutting flanges. Thereupon said key drops by gravity into a position wherein the converging edges 352 tend to wedge the flanges tightly together, and subsequent use of the structure tends to lock 90 them more tightly.

In Fig. 14 is shown an assembled form comprising six panel sections 200, constituting the side panels, two panel sections 20 constituting end panels, five outside corner 95 sections 28, and one inside corner section 29, all secured together by keys 35, and a suitable number of top and bottom horizontal angle bars 27, 270, 271, and 272. Said angle bars are engaged with the end 100 slots of the vertical flanges of the several sections, the lower angle bars constituting a base for the form, and the upper angle bars constituting a reinforced top which may also serve as a support for another set 105 of sections superimposed upon the section shown.

In Fig. 15 is illustrated means for tying together opposite side panels of the form in order to prevent spreading thereof when 110 the wall is poured. As shown in said figure, the plates 21 are formed with oppositely disposed openings 40 which receive looped portions 41 of a transversely extending wire 42. Into the loops 41 at the exterior of 115 the plates 21 are inserted nails 43. After the wall is poured, the nails 43 are removed, the panels 21 withdrawn laterally, and the loops 41 cut off, leaving the body of the wire 42 in the wall.

Having thus described my invention, I claim:

1. In a form for concrete structures, a series of panel sections having abutting vertical edge flanges provided with registering slots, and gravity keys in said slots for connecting the contiguous flanges of adjoining panels, said keys being bifurcated, and the legs thereof engaging the opposite faces of 125 said flanges, respectively. 130

2. In a form for concrete structures comprising a series of panels, a U-shaped gravity key for connecting said panels, said key comprising a rounded head and two depending legs having adjacent edges which converge toward said head.

3. A form for concrete structures comprising side panels having abutting flanges on their contiguous edges respectively, an angle bar constituting an outside corner of the form and having flanges abutting the flanges of adjacent panels, and angle bars engaging the ends of the abutting flanges of said panels and first named bar.

4. A form for concrete structures comprising side and end panels having abutting flanges on their contiguous edges respectively, an angle bar constituting an outside corner of the form and having flanges abutting the flanges of adjacent panels, and angle bars engaging the ends of the abutting flanges of said panels and first named bar.

5. A form for concrete structures comprising side panels and an inside corner unit composed of two plates rigidly connected at an angle to one another and having at their outer edges means whereby the same may be connected with the contiguous edges of adjoining side panels, and means for bracing said unit at its upper and lower corners.

6. In a form for concrete structures, an inside corner unit comprising two plates disposed at an angle to one another, an angle bar to which the inner vertical edges of said plates are secured, and angle bars secured to the outer vertical edges of said plates.

7. In a form for concrete structures, an inside corner unit comprising two plates disposed at an angle to one another, an angle bar to which the inner vertical edges of said plates are secured, and angle bars secured to the outer vertical edges of said plates, the projecting flanges of said angle bars being slotted.

8. A sectional form for concrete structures comprising flat panel sections having vertical edge flanges, inside corner sections each composed of two angularly disposed plates rigidly connected at their inner edges and having vertical flanges at their outer edges, outside corner sections each comprising a vertically disposed angle bar, the flanges of all of said sections being slotted, and gravity keys for connecting the contiguous flanges of adjoining sections.

9. A sectional form for concrete structures comprising flat panel sections having vertical edge flanges, inside corner units each composed of two angularly disposed plates permanently connected at their inner edges and having vertical flanges at their outer edges, outside corner sections each comprising a vertically disposed angle bar, means for detachably connecting the contiguous flanges of adjoining sections, and horizontal angle bars disposed respectively at the top and bottom of each aligned series of flat panel sections, each of said horizontal angle bars having a flange detachably connected with the edge flanges of the several sections.

In testimony whereof I affix my signature.
FRANK W. STEVENS.
